(57) CLAIM

The ornamental design for a single-sole shoe with red stripe and red sole, as shown and described.

DESCRIPTION

The file of this patent contains at least one drawing executed in color. Copies of this patent with color drawing(s) will be provided by the Office upon request and payment of the necessary fee.

FIG. 1 is a perspective view of a single-sole shoe with red stripe and red sole shaded to show the color red, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a rear view thereof;

FIG. 8 is a perspective view of a second embodiment of our new design of a single-sole shoe with red stripe and red sole, where the red portions are indicated using the USPTO convention of solid vertical lines for red or pink;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a rear view thereof.

The broken lines illustrating the channel on the red sole in the above described Figures are for illustrative purposes only and form no part of the claimed design.
